The ornamental design for a knife handle, as shown and described.

DESCRIPTION

The file of this patent contains at least one photograph executed in color. Copies of this patent with color photographs will be provided by the Office upon request and payment of the necessary fee.

FIG. 1 is a left side view of a knife handle showing a further embodiment of my new design;

FIG. 2 is a right side view thereof, wherein the right side is a mirror image of the left side;

FIG. 3 is a perspective view thereof;

FIG. 4 is a top view thereof; and,

FIG. 5 is a bottom view thereof.
